UNITED STATES PATENT OFFICE.

WILLIAM R. JEAVONS, OF CLEVELAND, OHIO.

DESIGN FOR A BOWL-SUPPORT FOR HYDROCARBON-BURNERS.

SPECIFICATION forming part of Design No. 35,692, dated February 4, 1902.

Application filed December 4, 1901. Serial No. 84,707. Term of patent 7 years.

To all whom it may concern:

Be it known that I, WILLIAM R. JEAVONS, a citizen of the United States, residing at Cleveland, in the county of Cuyahoga and State of Ohio, have invented and produced a new and original Design for a Bowl-Support for Hydrocarbon-Burners, of which the following is a specification, reference being had to the accompanying drawings, forming part thereof, and in which—

Figure 1 is a side view, and Fig. 2 is a perspective view, of my design.

In the views of the design thus shown there are three essential and conspicuous features which together make up the entire design, said features consisting of the appearance of a circular plain-surfaced and rather narrow body *a*, having a rim *b* about its top and a

pendant *c* at its center supported by the opposite branches *d*. These branches or arms *d* run to the outer edge and bottom of the body *a* and connect with the pendant *c* on a plane beneath the rim sufficiently low to disclose an open space between the bottom of said rim and the top surfaces of said branches or arms, especially where the pendant *c* is suspended.

What I claim is—

The design for a bowl-support for hydrocarbon-burners, substantially as described.

Witness my hand to the foregoing specification this 23d day of November, 1901.

WILLIAM R. JEAVONS.

Witnesses:

R. B. MOSER,
H. E. MUDRA.
